UNITED STATES PATENT OFFICE.

AUBREY B. LEECH, OF LOS ANGELES, CALIFORNIA.

APPARATUS FOR PRODUCING MOTION-PICTURE EFFECTS.

Application filed November 12, 1927. Serial No. 232,880.

This invention relates to illuminated signs wherein the illusion of motion is produced.

The main objects of this invention are to provide an improved form of advertising sign wherein the illusion of floating clouds traveling at variable speeds is produced, and to provide a sign of this character in which various objects can be arranged so as to produce the illusion of the objects floating on moving clouds.

An illustrative embodiment of this invention is shown in the accompanying drawing, in which:

Figure 1 is a front elevation of the improved device.

Fig. 2 is an enlarged section taken on the line 2—2 of Fig. 1.

Fig. 3 is a section taken on the line 3—3 of Fig. 2.

This invention is of the same general character as that shown in my United States Patent No. 1,369,751 dated February 22, 1921, wherein a rectangular box-like structure 1 is provided with a plurality of sources 20 of light 2 arranged side by side in independent units in spaced relation to each other.

Each of the sources of light is surrounded by a cylindrical screen 3 open at the bottom and having the top end provided with a plurality of radially disposed inclined vanes 4.

The vanes 4 are attached at their outer ends to the screen 3 and at their inner ends to a supporting hub 5 which is pivotally mounted on a framework 6 in the manner described and shown in the aforementioned patent.

The surfaces of all the cylindrical screens 3 are painted with polychrome colorings so that the various portions of the screens have different degrees of permeability to light rays. A translucent screen 7 is disposed in front of the cylindrical screens preferably parallel to the axes of the cylindrical screens, so that when the cylindrical screens are rotated the light therein will project variegated colorings onto the translucent screen to produce the illusion of colored moving clouds.

A transparent screen 8 is provided in front of the screen 7 in spaced relation thereto and is adapted to have any suitable object 12 pictured thereon.

In the present construction, the sign is shown having three sources of light and three cylindrical screens 3, 3^A and 3^B, the arrangement being such that a space is left on each side of the center cylindrical screen. Projection boxes 10 and 11 are located in the

spaces between the screens and each box is provided with a suitable source of light 13. The face thereof is provided with transparent or cut-out lettering 14, so that the light 60 in the box projects such lettering onto the translucent screen 7.

In the operation of this device, the heat generated by the sources of light 2 causes a current of air to pass up through the open bottom of the screens 3, striking the inclined vanes 4 and thereby rotating the screen on its hub 5, in the usual manner.

The coloring on the surfaces of the cylindrical screens is projected onto the translucent screen 7 so as to produce the illusion of moving clouds in various colors. Due to the cylindrical shape of the screens 3, 3^A and 3^B and the flat surface of the screen 7, the clouds appear to move slowest at the point where the cylindrical screen is nearest to the screen 7, and the farther from this point the faster the projected rays travel along the surface, thereby producing the effect of clouds moving at variable speeds, first slowly and then gradually faster until they blend into the fast moving projected rays of the next succeeding screen. They then appear to slow up until they reach the center point and then increase in speed again until they blend into those of the next following screen.

The object 12 pictured on the transparent screen 8, being in spaced relation to the screen 7, has the appearance of floating on the colored clouds in very life-like manner.

Although but one specific embodiment of this invention has been herein shown and described, it will be understood that numerous details of the construction shown may be altered or omitted without departing from the spirit of this invention as defined by the following claims.

I claim:

1. In a device of the class described, a plurality of sources of light arranged side by side, a cylindrical screen surrounding each of said sources of light, means for rotating said screens, variable coloring on each of said screens, different portions of said screens having different degrees of permeability of light rays, a translucent screen disposed in front of said cylindrical screens whereby the illusion of clouds moving at variable speeds is produced on said translucent screen, and a transparent screen disposed in front of said translucent screen in spaced relation thereto, said transparent screen having an object pictured

thereon whereby the illusion of said object floating on moving clouds is produced.

2. In a device of the class described, a plurality of sources of light arranged side by side, a cylindrical screen surrounding each of said sources of light, means for rotating said screens, polychrome coloring on each of said screens, different portions of said screens having different degrees of permeability to light rays, a translucent screen disposed parallel to the axes of said cylindrical screens whereby the illusion of clouds moving at variable speeds is produced on said translucent screen, and a transparent screen disposed in front of said translucent screen in spaced relation thereto, said transparent screen having

an object pictured thereon whereby the illusion of said object floating on moving clouds is produced.

3. A device of the class described comprising a pair of spaced translucencies one of said translucencies bearing the representation of a stationary scene, means for projecting a stationary image on the other translucency for providing a stationary background, and means for producing moving images on the last mentioned translucency for providing a moving background. 20 25

Signed at Los Angeles this 12th day of October, 1927.

AUBREY B. LEECH.
